UNITED STATES PATENT OFFICE.

HERBERT S. BALLIET, OF BETHLEHEM, PENNSYLVANIA.

SIGNAL DEVICE.

SPECIFICATION forming part of Letters Patent No. 705,549, dated July 29, 1902.

Application filed April 10, 1902. Serial No. 102,161. (No model.)

To all whom it may concern:

Be it known that I, HERBERT S. BALLIET, a citizen of the United States of America, residing at Bethlehem, in the county of Northampton and State of Pennsylvania, have invented a new and useful Improvement in Signal Devices, of which the following is a specification, reference being had to the accompanying drawing, forming part of the same, in which the single figure represents the lower part of the iron post of an automatic electric semaphore system and certain instruments placed therein, together constituting an embodiment of my invention, though it is by no means limited to the instrumentalities exhibited.

As stated, the view is of a part of a hollow iron post made in the form of a box or case C, with a door D shown open and partly broken away.

B B are batteries located within the case.

R is a relay, shown as supported on a table T.

F is a fan-motor provided with fans f and f', so placed as to force a current of air directly against the relay R, and w w' w² w³ w⁴ w⁵ w⁶ are the wire connections, which are only indicated, as their proper arrangement will be readily understood by any one skilled in the art of electric signaling.

In the operation of signaling systems, and particularly in operating automatic electric semaphores, many interruptions arise by reason of the fact that in cold weather relays, circuit-breakers, chains, gear-wheels, movable arms, levers, and other mechanisms are likely to be clogged by ice or frost. Even when inclosed in iron or wooden cases if the case be exposed to one temperature and then another moisture will collect within the case and upon coming in contact with the cold metallic parts will condense and will be deposited upon the instruments in the form of frost or ice and will tend to destroy the insulation, to clog the parts, and to seriously interfere with controlling the circuits and with the proper working of the devices, sometimes affecting levers, bearings, chains, and other parts and causing sluggish and imperfect action and sometimes freezing the parts solidly together, so as to prevent their being oper-

ated at all, and thereby causing great detention of traffic and liability to accident. I have discovered that if a current of air be forced against the parts liable to become thus clogged with frost or ice it will prevent the collection of moisture thereon, or if it has collected will result in its being rapidly removed, just as wind prevents the precipitation of dew upon grass, and to provide for thus protecting the apparatus I have devised a combination of devices in which a fan-motor is located within the inclosure with the instruments, preferably so set as to direct the current of air it causes in action directly upon the most delicate parts of the signaling mechanism, though I find that its exact location is not imperative, since its action will cause a movement of the air throughout the inclosure and accomplish the desired result even though the current be not thrown by the fan directly upon the mechanism to be protected.

I prefer to employ an electric motor-fan which may be run by a battery, as that is easiest of operation; but any other means of producing a current of air may be utilized with satisfactory results. I also prefer sometimes to use a motor with a fan at each end of the axle, as that renders it certain that the mechanism of the fan-motor will be protected equally with the other mechanism.

The conditions under which frost and ice collect in the inclosure usually only exist from sunrise to sunset, so that it is not necessary to keep the fan in perpetual motion, and provision may be readily made to conform to this situation by arranging to cut out the fan-motor at times when its operation is not necessary and to cut it in when it is desired, thus saving battery energy and reducing the cost of operation. It may be run by currents of high or low potential, as may be most convenient; but I prefer to operate it on a circuit separate from that of the signaling device.

The invention, as will readily be understood, consists in the combination, with the instrument or instruments of a signaling system, of means for producing a current of air and causing it to circulate about said instrument or instruments, and the special means

or mechanism employed is not of particular moment, though, as already remarked, I prefer to use an electric fan-motor.

What I claim, and desire to secure by Letters Patent, is—

- 5 1. The combination with a signal-box, containing an instrument of a signaling system, of means for producing a current of air, located and arranged, substantially as described, whereby said current of air will be caused to circulate over and about said instrument.
- 10 2. The combination with a signal-box, containing an instrument of a signaling system, of means for producing a current of air, located within the signal-box, and arranged substantially as described, whereby said current of air will be caused to circulate over and about said instrument.
- 15 3. The combination with a signal-box, containing an instrument of a signaling system, of a fan and means for operating it located and arranged substantially as described, whereby said current of air will be caused to circulate 20 over and about said instrument.
- 25 4. The combination with a signal-box, containing an instrument of a signaling system, of a fan and means for operating it, located within the signal-box, and arranged substantially as described, whereby said current of air will be caused to circulate over and about said instrument.
- 30 5. The combination with a signal-box, con-

taining an instrument of a signaling system, of an electric motor-fan located and arranged 35 as described, together with means for operating it located and arranged substantially as described, whereby said current of air will be caused to circulate over and about said instrument.

40 6. The combination with a signal-box, containing an instrument of a signaling system, of an electric motor-fan located in the signal-box with said instrument, and arranged as described, together with means for operating it 45 located and arranged substantially as described, whereby said current of air will be caused to circulate over and about said instrument.

7. A semaphore signaling device composed 50 of a post and signal-box provided with signaling devices, in combination with an electric fan-motor, located within said signal-box and arranged as described, together with suitable connections and energizing apparatus, 55 all arranged and combined substantially as and for the purpose set forth.

In testimony whereof I have signed my name to this specification, in the presence of two subscribing witnesses, this 27th day of 60 March, 1902.

HERBERT S. BALLIET.
